UNITED STATES PATENT OFFICE.

GEORGE N. HEIN, OF SAN FRANCISCO, CALIFORNIA.

SYRINGE.

Application filed August 30, 1924. Serial No. 735,126.

To all whom it may concern:

Be it known that I, GEORGE N. HEIN, a citizen of the United States, residing in the city and county of San Francisco and State of California, have invented certain new and useful Improvements in Syringes, of which the following is a specification.

The present invention relates to improvements in medical appliances, more particularly syringes, and the invention has for one of its objects to provide a syringe in the use of which the operator has complete power control from the minimum to the maximum requirements for injecting fluids, gases and medicated solutions into various cavities and tissues of the body, or withdrawing matter from cavities or in pumping out the stomach, pleural, or abdominal cavities, and the elimination of matter from all sinuses, viz:—antra and frontal, and deep, obscure, and superficial abscesses.

A further object of the invention is to design a syringe adapted especially for injecting large quantities of solutions intravenously, such as salvarsan, and numerous intravenous products, where a greater dilution of the solution is preferable to the strength of concentrated form injected under present conditions.

30 A further object is to provide an apparatus whereby the operator is enabled to inject directly into the tissues any desired strength of solution contained within an ampul directly therefrom without transferring the solution to a separate container.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to without departing from the spirit or sacrificing any of the advantages of the invention.

In the drawings disclosing the invention:—

50 Fig. 1 is a view in plan of the preferred embodiment thereof.

Fig. 2 is a similar view of a modified construction,

55 Fig. 3 is a view in elevation of an ampul with the end portions to be broken off indicated by transverse designations.

In the drawings, wherein like characters

of reference designate corresponding parts, 1 indicates a cylindrical shell adapted to be closed by a cover resting on the peripheral edge of the circumferential wall 3 of the 60 shell disposed at right angles to the base 4 of said shell. Upwardly from the base 4 in the center of the shell 1 extends a shaft 6. On one end it carries a plate 7, and on its opposite end mounts a handle 8 of a length to extend beyond the periphery of the shell 1. The plate 7 at equidistant points about its surface rotatably mounts on bearings 9 compression rollers 10, the surface of each of which lies in slight spaced relation to the 70 inner face of the wall 3 of the shell 1.

At diametrically opposite sides, the wall 3 is formed with pairs of tubular passages 11 through which extends lengths of readily compressible elastic tubing 12 and 12'. The 75 respective stretches of tubing within the shell 1 following the contour of the inner surface of the wall 3 and lying exteriorly of the tube compression rollers 10. The elastic tube 12 at its inlet end mounts a two way 80 valve controlled casing 13 with which connects the outlet of a container 14 for holding a body of liquid, for example normal salt solution, which it is desired to intermix with the main body of medicine or solution employed as an injection. With the valve casing 13 also connects a pipe 15 mounting at its end an ampul 16. The ampul is preferably of glass construction, and provided with sealed ends 17 and 17', the portion of 90 the ampul end adjacent the seal portion 17' being bulged or rounded as at 18. The end portion 17' of the ampul is broken off on the line indicated and the end of the flexible tube is inserted to overlie the portion 18, the 95 bulge serving as a uniting connection between the ampul and tube.

Prior to operation, the upper end 17 of the ampul is broken on the line indicated to admit air and permit the flow of the contents from the opposite end thereof. The elastic tubing sections 12 and 12' are interconnected in a two-way-valve casing 19, and from the casing extend the nipples 20 and 21, the former connecting through a flexible tube 22 with the usual form of hypodermic needle 23, the tube mounting a glass observation section 24, which facilitates the operation of the apparatus. The latter nipple 21 connects with a drain tube 25, and the 110 opposite end of the tube 12' terminates in a drain outlet 26. It will be observed that

when the device is in use the sections of elastic tubing within the shell 1 are advancingly compressed by the travel of the compression rollers circumferentially within the shell, and the fluid in advance of the respective rollers is forced therefrom.

By this apparatus and the employment of the elastic tubes 12 and 12' it is possible to inject the solution and to drain from the 10 diseased area at one operation. It is also possible without the aid of check valves to force a continuous stream of fluid into the desired area. The employment of elastic tubing relieves the shock of the pressure of 15 the fluid as injected into the diseased area, as the elasticity of the tubes is capable of absorbing the pulsations of the heart when the injection is made into the arteries.

In the modified construction, I have eliminated 20 the drain pipe 12' and have constructed the compression roll apparatus with but one roller 10.

It will be observed that the first ampul has two breakable ends 17 and 17', and that 25 the enlargement 18 inwardly from the end

17' affords a connection or globe to be gripped by the end of an elastic tube when the ampul is directly connected with the tube end.

I claim:

A hypodermic syringe including a source of medicinal solution, a hypodermic needle for connection with an area to be treated, an elastic tube connecting the same and through which the solution is conveyed under pressure to the needle, a second tube constituting a drain, and connecting at one end with the area treated, and at its opposite end discharging to the atmosphere, a casing through which the tubes pass and provided with a wall against the inner face of which said tubes lie in opposing relation, and a member rotatably mounted within the casing for advancingly compressing the tubes against the wall for continuously conveying the solution in opposite directions through the respective tubes.

In testimony whereof I have signed my name to this specification.

GEORGE N. HEIN.
